HINGE-AXIS ARTICULATOR

Theodore A. Bodine, Summit County, Ohio

Application October 28, 1942, Serial No. 463,605

19 Claims. (Cl. 32—32)

This invention relates to a hinge-axis articulator. It can be used in the construction of artificial teeth and as a diagnostic instrument for measuring mutilations to the cusps of teeth and the temporomandibular joint. It may be set to define any particular condylar curve produced by teeth moving in an unstrained relation from the protruded to the retruded position. It may be set to define a different curve at each end of the condylar axis. When not set to define any particular curve it is adapted to define any curve that the teeth may make in a strained relation. In this latter case it may be adjusted to move only within the limits permitted by the condylar displacement between the position when there is a pull on the capsular ligament as in chewing a hard bolus of food between the back teeth and the position when there is a displacement of the meniscus as when chewing on a hard bolus of food between the front teeth.

In the preferred design of this instrument two incisal guidances are provided for the lateral movement of the teeth, and the angle of their movement may be reproduced to determine the cusp height and incisive bite of the teeth.

The instrument is preferably provided with Bennett controls and a scale to determine facial widths. Other scales may be provided as for example, those shown in the drawings. The nature and range of the movement of the various parts of the instrument and its adaptability for various uses will be more fully explained in what follows.

The invention will be further described in connection with the accompanying drawings.

Fig. 1 is a plan view of the instrument;

Fig. 2 is a front elevation;

Fig. 3 is a rear elevation;

Fig. 4 is a section on the line 4—4 of Fig. 3;

Fig. 5 is an enlarged detail of a locking mechanism described below;

Fig. 6 shows the relation between different elements of the axis support and is largely a section on the line 6—6 of Fig. 1; and

Fig. 7 is a detail with part of one of the uprights 31 broken away and is largely a section on the line 7—7 of Fig. 1.

The condylar axis 4 supports one end of the bracket 2 which is provided with a finger lift 3 for raising and lowering its front end. This bracket is preferably flanged at 4 and 5 to accommodate two incisal guidance pins 6 and 7 which move across the face of the incisal guidance plates 8 and 9. These incisal guidance plates are supported in the cradles 10 by the set screws

11. The cradle is adapted to swivel in a horizontal plane on the post 12. The screw 13 locks the post (not shown) on which the cradle 10 swivels, so as to prevent rotation of the cradle. The incisal guidance plates swivel on the set screws 11 which are provided with knurled heads so that they may be tightened to hold these plates in any plane. The plane of each incisal guidance plate may be adjusted independently of the other.

The condylar axis 4 is supported by the two pistons 20 which are mounted to slide in the cradles 21. The set screws 22 are provided to lock each piston in any desired position regardless of the position of the other. The knurled nuts 23 and 24 may be set in any position to limit the sliding movement of the piston to any desired range. The nuts 23 limit the extent of the movement produced by a pull on the capsular ligaments caused by chewing on a hard bolus of food between the back teeth. The nuts 24 may be placed to control the displacement of the menisci caused by pressure when biting on a hard bolus of food between the front teeth. The cradle 21 is supported by the plate 25 and this is pivoted to the block 26 by means of a pivot 27 which passes through the block 26 directly in line with the piston 20. The piston 20 therefore may be rotated about the pivot 27 and may be moved longitudinally.

A projection on the front of the block 26 fits snugly between the uprights 31 and is held in place by the locking screw 32. By tightening this screw the position of the block 26 can be maintained at any desired distance from the base of the uprights 31. One end of the threaded shaft 33 is embedded in the block 26 and the vertical movement of the block is controlled by turning the knurled nut 34. The projection 35 on the under side of the nut 34 turns in the yoke 36 which is supported by the uprights 31. The guide plate 37 comprises a projection which fits snugly between the uprights 31 and this serves to steady the block 26 and provide for unvarying vertical movement thereof.

The block 26 is rotatably mounted on the graduated annular ring 40. In the preferred form of the instrument shown in the drawings this is accomplished by supporting the uprights 31 on the block 42. The projection 43 on this block 42 fits snugly within the annular ring 40. It is held in place by the plate 44 which is bolted to the projection 43. Any suitable means for locking the projection 43 in any desired position in the annular ring may be provided. In the in-

strument shown in the drawings this is accomplished by a bolt with a knurled head 46 which is threaded into a small plate 47 which is cut out of the plate 44. By tightening the knurled head the small plate 47 is drawn to the block 42 and the annular ring is squeezed between the plate 44 and the block 42 and the block 42 is thus held against rotation around the annular ring. On loosening the bolt 46 the block 26 may be rotated around the annular ring 40 until it assumes any desired position.

When the set screw 22 is loosened the piston 20 is free to slide in the cradle. The block 26 which carries the pivot 27 may be rotated around the annular ring 40 and set at any position by tightening the set screw 46. With this adjustment the condylar axis may be made to describe a curve of any desired radius, the center of which may be located in any position around the condylar axis. By adjusting the nuts 23 and 24 and loosening the set screw 22 the longitudinal movement of the piston 20 may be limited within any desired range. With this adjustment the condylar axis may be moved through any curve the jaws may make in any strained relation. The movement of each end of the axis is independent of the movement of the other end and may be individually controlled regardless of the adjustment.

Because the movements of each end of the condylar axis are independent of the movements of the other end it is desirable to have two incisal guidance pins as shown in the drawings and incisal guidance plates which are individually adjustable, all as shown in the drawings.

When setting up the instrument the mounting rings are fastened in place by the mounting plate screws 50. Then with records taken from the mouth the instrument is set with the teeth in the unstrained relation by tightening the set screw 22 after the block 26 has been rotated to the proper position and locked by tightening the set screw 46. Tightening the set screw 22 locks the piston 20 with the condylar axis at the proper distance from the pivot 21. The incisal guidance pins are then locked at the proper length. The upper end of each incisal guidance pin is threaded at 52 into a head 53 of the supporting bracket. Its length is determined by threading it in or out of the bracket head. After the length is properly adjusted the pin is locked by tightening the locking screw 51.

The annular rings 40 are supported by the plates 60 which slide on the rail 61 and may be locked in any position by the set screws 62. The rail 61 preferably carries a scale as in Fig. 3 so that the facial width determined by the position of the plates 60 may be measured and recorded.

The Bennett controls 70 are mounted on the pins 71 and are adapted to swivel on the top of the posts 72 which support the rail 61. They may be set in any position by tightening the knurled nut 73. A slit 74 is provided in the base of each Bennett control through which the scale 75 which is permanently fixed to the post 72 is visible. The angle of lateral movement of the jaw may be determined by rotating the Bennett control so that the end of the condylar axis moves against the face 76 of the raised sector 77. This position may be fixed by tightening the nut 73 and the angle of any position may be read directly on the scale 75.

The block 42 and the plate 44 are cut away at 79 to permit horizontal retrusion of the condylar

axis which however is normally prevented by the setting of the set screw 80.

I claim:

5 1. A hinge-axis articulator which comprises a condylar axis which hingedly supports a bracket to which at least one incisal guidance pin is affixed, a support rotatable in a vertical plane and a piston which supports the condylar axis and is adapted to move longitudinally with respect to itself which piston is pivotally supported by said support.

15 2. A hinge-axis articulator which comprises a condylar axis which hingedly supports a bracket to which at least one incisal guidance pin is affixed, a support rotatable in a vertical plane, a piston which supports the condylar axis and is adapted to move longitudinally with respect to itself which piston is pivotally supported by said support and means for locking said piston in any position.

20 3. A hinge-axis articulator which comprises a condylar axis which hingedly supports a bracket to which at least one incisal guidance pin is affixed, a support rotatable in a vertical plane, a piston which supports the condylar axis and is adapted to move longitudinally with respect to itself which piston is pivotally supported by said support and means for limiting the radial movement of said piston.

25 4. A hinge-axis articulator which comprises a condylar axis which hingedly supports a bracket to which at least one incisal guidance pin is affixed, a support rotatable in a vertical plane, a piston which supports the condylar axis and is adapted to move longitudinally with respect to itself which piston is pivotally supported by said support, means for limiting the radial movement of said piston and means for locking the piston in any position.

30 5. A hinge-axis articulator which comprises a condylar axis which hingedly supports a bracket to which at least one incisal guidance pin is affixed, a support rotatable in a vertical plane, a piston which supports the condylar axis and is adapted to move longitudinally with respect to itself which piston is pivotally supported by said support and means for locking the support in any position.

35 6. A hinge-axis articulator which comprises a condylar axis which hingedly supports a bracket to which at least one incisal guidance pin is affixed, a support rotatable in a vertical plane, a piston which supports the condylar axis and is adapted to move longitudinally with respect to itself which piston is pivotally supported by said support, means for locking the support in any position and means for locking the piston in any position.

40 7. A hinge-axis articulator which comprises a condylar axis which hingedly supports a bracket to which at least one incisal guidance pin is affixed, a support rotatable in a vertical plane, a piston which supports the condylar axis and is adapted to move longitudinally with respect to itself which piston is pivotally supported by said support, means for locking the support in any position and means for limiting the radial movement of the piston.

45 8. A hinge-axis articulator which comprises a condylar axis which hingedly supports a bracket to which at least one incisal guidance pin is affixed, a support rotatable in a vertical plane, a piston which supports the condylar axis and is adapted to move longitudinally with respect to itself which piston is pivotally supported by said support.

support, means for locking the support in any position, means for limiting the radial movement of the piston and means for locking the piston in any position.

9. A hinge-axis articulator which comprises a condylar axis which hingedly supports a bracket to which at least one incisal guidance is affixed, two pistons which separately support the condylar axis and are adapted to move longitudinally with respect to themselves, means for separately pivotally supporting each piston at a position on the arc of a circle with an adjustable radius and means for varying the distance between said pistons.

10. A hinge-axis articulator which comprises a condylar axis which hingedly supports a bracket to which at least one incisal guidance is affixed, two pistons which separately support the condylar axis and are adapted to move radially with respect thereto, means for separately pivotally supporting each piston at a position on the arc of a circle with an adjustable radius, means for varying the distance between said pistons, means for independently limiting the radial movement of each piston and means for independently locking each piston in any position.

11. A hinge-axis articulator which comprises a condylar axis supported by a piston which, in turn, is supported by a pivot adapted to be located at any desired distance from the condylar axis, the pivot being adapted to be moved to any desired position around the condylar axis.

12. A hinge-axis articulator which comprises a condylar axis supported toward each end by a piston which is pivotally supported, each end of the pivots being adapted to be moved independently to any desired position around the condylar axis, each end of the condylar axis being free to move independently of the other.

13. A hinge-axis articulator which comprises a condylar axis the two ends of which are free to move independently of one another, two incisal guidance pins each substantially parallel to one another and substantially perpendicular to an axis parallel to the condylar axis and offset therefrom, said pins being hingedly supported from the axis to trace the different movements of the two ends of the axis.

14. A hinge-axis articulator which comprises a condylar axis, two incisal guidance pins each substantially parallel to one another and substantially perpendicular to the condylar axis and hingedly supported thereby, two pistons which separately support the condylar axis and are adapted to move longitudinally with respect to themselves, and independent means rotatably mounted for pivotally supporting each piston.

15. A hinge-axis articulator which comprises a condylar axis, two incisal guidance pins each substantially parallel to one another and substantially perpendicular to the condylar axis and hingedly supported thereby, two pistons which separately support the condylar axis at a variable

distance to one another and are adapted to move longitudinally with respect to themselves, independent means rotatably mounted for pivotally supporting each piston, means for separately limiting the radial movement of each piston and means for independently locking each piston in any position.

16. A hinge-axis articulator which comprises a condylar axis the two ends of which are free to move independently of one another, two incisal guidance pins each substantially parallel to the other and substantially perpendicular to an axis parallel to the condylar axis and offset therefrom, said pins being supported from the axis to trace the different movements of the two ends of the axis, and an incisal guidance for each of said incisal guidance pins, each incisal guidance being adapted to be rotated about a vertical axis and also about a horizontal axis.

17. A hinge-axis articulator which comprises a condylar axis which hingedly supports a bracket to which two substantially parallel incisal guidance pins are independently slidably and lockably affixed substantially perpendicular to the condylar axis, two annular rings encircling the condylar axis spaced an adjustable distance from one another and having substantially the same axis, a support lockably connected with each, each of which supports is of adjustable length and is adapted to be independently rotated about the axis of its annular ring and comprises a horizontal pivot mounting, two pistons each of which slidably supports the condylar axis and is perpendicular thereto and is pivotally affixed to one of said horizontal pivot mountings so as to be longitudinally movable with respect to itself, means for separately limiting the longitudinal movement of each piston and separate means for locking each piston to provide any desired distance between the condylar axis and the pivot mounting of that piston.

18. A hinge-axis articulator with a condylar axis supported within annular rings at its respective ends, a pivot which is supported at a variable distance from the center of each ring and rotatable thereabout, means for locking the pivot at any distance from the center of the ring in any one of many directions therefrom, a piston which supports the axis pivoted on each pivot, the axis being slidable lengthwise with respect to the piston, means for varying the limits of the stroke of the piston and means for locking it at any position in its stroke.

19. A hinge-axis articulator provided with a condylar axis, two annular rings located in substantially parallel planes which encircle the axis near opposite ends thereof, a pivot mounted on each ring so that it is rotatable about the center of its ring and adapted to be moved a variable distance from the center of its ring, and a piston mounted on each pivot, the condylar axis being supported near each end by one of said pistons.

THEODORE A. BODINE.

CERTIFICATE OF CORRECTION.

Patent No. 2,371,795.

March 20, 1945.

THEODORE A. BODINE.

It is hereby certified that error appears in the printed specification of the above numbered patent requiring correction as follows: Page 1, second column, line 19, for "liaments" read --ligaments--; page 3, first column, line 19, claim 10, for "radially" read --longitudinally--; line 20, same claim, for "thereto" read --to themselves--; line 35, claim 12, strike out "end"; and that the said Letters Patent should be read with this correction therein that the same may conform to the record of the case in the Patent Office.

Signed and sealed this 19th day of June, A. D. 1945.
